[57] CLAIM

The ornamental design for a golf bag, as shown and described.

DESCRIPTION

FIG. 1 is a perspective view of a golf bag showing my new design;

FIG. 2 is a top plan view thereof;

FIG. 3 is a rear elevational view thereof;

FIG. 4 is a side view, with the opposite side being a mirror image thereof;

FIG. 5 is a front elevational view thereof;

FIG. 6 is a bottom plan view thereof;

FIG. 7 is a perspective view of a second embodiment; and,

FIG. 8 is a perspective view of a third embodiment.

The second and third embodiments are identical to the first embodiment with the exception of the additional side pocket.

The broken line showing of environment in FIG. 1 is for illustrative purposes only and forms no part of the claimed design.
